UNITED STATES PATENT OFFICE.

A. D. WHITMORE, OF HOUSATONIC, MASSACHUSETTS.

IMPROVED FOLDING CHAIR.

Specification forming part of Letters Patent No. 40,526, dated November 3, 1863.

To all whom it may concern:

Be it known that I, ALBERT D. WHITMORE, of Housatonic, in the county of Berkshire, State of Massachusetts, have invented a new and Improved Folding Chair; and I hereby declare the following a full and exact description thereof, reference being had to the accompanying drawings, and to the reference letters thereon.

The seat of the chair may be made a frame, *a a*, and filled in with cane or flag, or covered with carpet or any other suitable material, or the seat may be a wood bottom of itself constituting the frame. Below the seat, in place of the rounds usually put into chairs, is a second frame, *b b*, of similar size and form to the seat, and in this particular differing from all other chairs known to the inventor. To the seat *a a* and this frame *b b* the legs and posts of the chair are attached by pegs, bolts, or screws, and turn on them as pivots. The chair-back may be of any style agreeable to the builder.

To support the front of the chair when open, two braces, *c c*, are attached to the back-posts below the seat, and extending to and locking into a metallic guide or groove, *d d*, which is secured to the seat. A button or latch, *e*, is attached to the guide or seat frame, and, dropping down back of the hook of the brace, holds the chair spread, and loses its hold when inverted and allows the chair to close. These braces may be attached to the front legs or the posts above the seat, or to the seat itself, and act upon the guide on the back.

What I claim as my invention, and desire to secure by Letters Patent, is—

The combination of the frame *b b* with the legs and rounds, and the frame *a a*, the braces *c c*, the guide *d d*, and latch *e*, substantially as and for the purpose specified.

A. D. WHITMORE.
